[57] ABSTRACT

A wall construction, particularly but not solely for use as a room divider, or partition, has a rectangular frame defining an opening for a wall panel that may desirably be a translucent, ornamentally configured plastic sheet or the like. Bounding the opening is a rib forming an abutment against which the panel may seat, and cooperating with the rib in clamping the panel in place is a retaining strip, preferably of T-shaped cross section, seated in a groove formed in the frame and laterally spaced from the abutment. The several tongues of the strip are all of different lengths but of the same thickness, so that any one of the tongues or legs can seat in the groove to dispose a selected one of the three tongues in engagement with the panel. The cross member of the T represented by the cross sectional shape of the strip may also bear against the panel. This permits a single strip to be usable for clamping any of four panel thicknesses.

WALL CONSTRUCTION

BACKGROUND OF THE INVENTION

1 Field of the Invention

The invention pertains to the art of wall constructions, partitions, or room dividers in general, and in particular to the art of fabricating structures of this type, often in situ, through the medium of a minimum number of basic components cooperating in such fashion that in such static structures as buildings, interior partitions or dividers may be erected by disposing a panel in a peripheral frame, and holding it in place by inserting a retaining strip in a grooved portion of the frame.

2 Description of the Prior Art

It is obviously highly desirable to provide room partitions or dividers that can be erected to any desired height or length, as for example in a modular arrangement, swiftly and easily, and with the use of a minimum number of inexpensively fabricated components. The provision of such a divider especially is desirable in that it permits the ordinary householder, often possessing little skill in carpentry, to erect an attractive room divider, and at a comparatively low cost. Heretofore, in the art, it has been known, as a general proposition to provide room dividers of this general category. However, certain deficiencies in the prior art construction have been noted, and it is proposed to remedy these deficiencies through a novel construction to be described hereinafter.

The problem in the prior art, it is believed, has been that sufficient versatility has not been designed into the room dividers of this type. As a result, it is necessary to stock a relatively large number of components, including frame members, panels, and retaining strips or equivalent devices. This, in turn, has caused the unit cost to be increased to an undesirable extent, as a result of which the commercial feasibility of these devices has not been exploited as much as it should be.

SUMMARY OF THE INVENTION

Summarized briefly, the present invention utilizes frame members which are of like cross section, and which can be cut or otherwise formed to a prescribed number of modular lengths. As a result, room divider frame structures can be erected by assembling these frame members in rectangular configurations. And, in association with the peripheral frame members so assembled and erected, the invention includes the provision of vertical or horizontal divider frame members, which can be used to extend between opposed outer frame sections, to divide a single panel receiving opening into two or more such openings.

The invention further includes a construction wherein each frame member has a longitudinal rib laterally spaced from a longitudinal groove, the groove and rib being in parallel relation and extending continuously about the panel receiving opening.

A panel seats against the rib, and is clamped in place through the provision of a retaining strip of T-shaped cross section, having three legs of different lengths, any of which may engage in the groove. This allows any of three legs of different lengths, or for that matter the cross member of the T, to bear against the panel. In this way, although a single retaining strip may be provided as a stock item, any of four different panel thicknesses can be clamped between the strip and rib.

BRIEF DESCRIPTION OF THE DRAWING

FIG. 1 is an elevational view of a room divider according to the present invention, shown fragmentarily;

5 FIG. 2 is an enlarged, fragmentary perspective view of one of the sides of the divider;

FIG. 3 is an enlarged cross sectional view through the base portion of the divider, taken on line 3-3 of FIG. 1;

10 FIG. 4 is a sectional view, on the same scale as FIG. 3, taken on line 4-4 of FIG. 3;

FIG. 5-7 are views similar to FIG. 4, showing the retaining strip in different positions in which it may be used in accordance with the invention; and

15 FIG. 8 is a view like FIGS. 5-7 showing a modified form.

DESCRIPTION OF THE PREFERRED EMBODIMENT

20 Referring to the drawings in detail, a room divider is illustrated in FIG. 1, extending between ceiling C and floor surface F. The room divider, in the illustrated example, includes a frame structure generally designated 10, which is erected as an upright frame of rectangular form, defining and extending about a correspondingly rectangular, panel-receiving opening 11.

In the illustrated example, the vertical members of the divider are extended above and below the horizontal members and include spring-pressed extensions 13 at their upper ends, and feet 15 at their lower ends, a construction which adapts the divider for erection in rooms varying as to ceiling height. And, this arrangement permits swift and easy installation without the use of tools, etc.

35 Extending continuously about the opening is a rib 12 which in the illustrated example, but not necessarily, is disposed between the opposite faces 13 of the frame. The rib could, if desired, be flush with one of said faces.

40 In any event, the rib 12 extends longitudinally of the top, bottom, and sides of the frame, so as to extend completely around the opening.

45 Also extending continuously about the edge of the opening, is a groove 14, formed in the frame structure in laterally spaced, parallel relation to the rib.

50 A retaining strip assembly generally designated 16, comprises a plurality of individual strips, each of which extends along an associated portion of the frame. Retaining strip assembly 16 cooperates with the rib 12 in clampably engaging therebetween a panel 18. Panel 18, in a preferred embodiment, can be of translucent, colored plastic, one or both faces of which may be ornamenteally configured if so desired, although this is of course not critical to successful use of the invention. The panel may be completely opaque, or for that matter completely transparent, if this should be so desired.

55 In any event, the panel is formed as a rectangular sheet, completely filling the associated opening, and when mounted in place, will be firmly and immovably engaged between the rib and retaining strip.

60 The retaining strip that extends along each side of the structure is T shaped in cross section, though not formed as a symmetrically shaped T when so viewed. Rather, as noted from any of FIGS. 2-7, the retaining strip, by reason of its asymmetrical T shaped cross section, is provided with three legs 20, 22, 24 of different

lengths but of the same thickness. There is thus provided a long leg 20, a short leg 22, and a medium leg 24. In referring to the "length" of the legs, it is understood that the intention here is to consider said lengths of the legs as viewed in cross section, as for example in FIG. 4. When so viewed, it is clearly seen that the legs are of like thickness, but differ from one another in respect to the distance they extend from the location of their juncture.

By reason of this arrangement, any leg can be seated in groove 14, the depth of which is equal to or greater than the length of the longest leg 20. For example, in FIGS. 3 and 4, the leg 24 is seated in the groove 14, with leg 20 extending across the space between groove 14 and rib 12. Leg 20, the longest leg, is thus used in FIG. 3 and 4 to cooperate with the rib 12 in clamping the panel 18 therebetween. Since the long leg 20 terminates only a short distance from the rib 12, the panel 18 may be relatively thin.

The same retaining strip can be used, however, to accommodate a panel 18 a. This panel, shown in FIG. 5, is substantially thicker than the panel 18, and in this arrangement, the leg 22 is used to bear against the panel, with the leg 24 still being used for engagement in the groove 14. Leg 22, being the shortest leg, permits clamping of a panel of substantial thickness in the frame structure.

In FIG. 6, a panel 18 b, thinner than panel 18 a but thicker than panel 18, is used. In this arrangement, the leg 24 of intermediate length is used for the purpose of clamping the panel against the rib 12. In this event, the longest leg 20 seats in groove 14 (although one could alternatively seat the shortest leg 22 in the groove, if so desired).

In the FIG. 6 arrangement, a recess is defined between the panel and the leg 22, and if desired this can be used to accommodate a filler strip 25, which could alternatively be a flexible sealing strip or the like. This is, of course, at the option of the user and may depend to some degree upon the installation conditions and the location at which the wall or partition is to be used.

In FIG. 7, the retaining strip is shown in yet another position, in which the cross member of the T, defined by the coplanar legs 20, 22, is used to bear against a panel 18 c greater in thickness than any of the other panels described above.

It is thus seen that a single retaining strip can be disposed in any of four positions, to accommodate panels of four different thicknesses. In other words, a single frame member, and a single retaining strip, cooperate to clampably engage four different panel thicknesses in the illustrated arrangement.

In some instances, the retaining strip might be of L shape in cross section, rather than of a T-shaped cross section, so that there would be only two legs rather than three. In this arrangement, shown in FIG. 7, legs or tongues would be of different lengths but of the same thickness, permitting any of three different panel thicknesses to be accommodated. The strip assembly 16 a here includes legs 20 a, 24 a of different lengths. Either of these can abut a panel 18. Or, by turning the strip to the dotted line position, a third panel thickness can be accommodated.

In erecting the wall, I would provide, in a preferred embodiment, a base frame member 26, disposed horizontally.

A horizontal top frame member 28 is spaced above the bottom frame member, through the provision of side frame members 30, and (if desired) one or more vertical divider members 32. The divider members separate the single large opening 11 into a plurality of openings. The divider member is similar to the members 26, 28, 30 except for the fact that it will have ribs and grooves 12, 14 respectively on opposite faces, rather than on one face or longitudinal edge only. Thus, as seen in FIG. 1, the divider frame member 32 receives retaining strips 16 at opposite sides of said divider frame member.

It will be understood that the top and bottom frame members, as well as the members 30, 32, can be pre-cut in any of a plurality of various modular lengths, so that one can select from stock said frame members, according to the installation requirements as regards the particular room divider that is to be erected. Also, the panels 18 can be selected from stock, correspondingly. The ends of the horizontal members would in the illustrated example have end tongues and grooves mating with the grooves 14 and ribs 12, respectively, of the side frame members 30 and divider members 32.

In this way, the horizontal frame members 26, 28 can be adjusted along the lengths of the side and divider frame members 30, 32 respectively, to selected locations. Then, panels 18 can be seated in the resulting openings 11, against the ribs 12 bounding said openings. Retaining strips as hereinbefore described are then inserted in the grooves 14, being positioned in any of the positions shown in FIGS. 4-7 according to the thickness of the particular panel to be clamped thereby. The retaining strips can be adhesively engaged in the grooves 14, or screws, small nails, or the like, not shown, can be driven through the retaining strips to hold them in place. It is also within the scope of the invention to simply wedge the legs of the retaining strips into their associated grooves 14.

It will be seen that the arrangement is possessed of a high degree of versatility, despite the relatively small number of cross sectional configurations used. A single cross sectional configuration for the frame member 26, 30 or 28 as the case may be, and a single cross sectional configuration of the cooperating retaining strip, permits accommodation of four different panel thicknesses, as compared to prior art devices in which four different retaining strip cross sections, or four different frame member cross sections, were required for the same purpose. This reduces considerably the overall cost of room dividers of the type illustrated and described. Especially is this necessary when one considers that it is essential in any event to maintain frame members of different lengths, since room dividers are erected to various heights and lengths. This in many instances multiplies undesirably the total number of frame members that must be stocked, if said frame members are to be used for accommodating panels of different thicknesses. In accordance with the present invention, this excessive stocking requirement is obviated, through the medium of the novel cross sectional construction illustrated, all without increase in the cost of fabricating any of the individual strips of frame members.

I claim

1. A wall construction, especially for use as a room divider or the like, comprising:
  - an upright frame structure having a panel-receiving opening, the edge of which is formed with an abutment means and with a groove transversely spaced from and extending in a mutually parallel relationship with said abutment means;
  - a panel seated in said opening against the abutment means; and
  - a retaining strip seated in the groove and bearing against the panel to clampably engage the same between the abutment means and strip, said strip being of an asymmetrical T-shaped cross-section

to define three legs, two of which are coplanar, the third leg being offset from the mid-point of the combined length of the two coplanar legs and extending normally to the plane of said two legs, whereby each of said legs is of a length different from the length of either of the other legs, any one of said legs engaging in the groove with another of the legs bearing against the panel, said legs being of the same thickness for extension of any leg into the groove, said groove being of a depth not less than the length of the longest of the legs, thus to optionally retain different panels of at least four different thicknesses.
